DESIGN FOR A STOKER OR THE LIKE

John J. McGlone, Harvey, Ill., assignor to Whiting Corporation, Harvey, Ill., a corporation of Illinois

Application August 16, 1937, Serial No. 71,111

Term of patent 3½ years

To all whom it may concern:

Be it known that I, John J. McGlone, a citizen of the United States, residing at Harvey, Cook County, Illinois, have invented a new, original, and ornamental Design for a Stoker or the like, of which the following is a specification, reference being had to the accompanying drawing, forming part thereof.

In the drawing:

like embodying my new design and the dominant features of my design reside in the portions shown in full lines.

I claim:

The ornamental design for a stoker or the like, substantially as shown and described.

JOHN J. McGLONE.
